UNITED STATES PATENT OFFICE.

HOWARD J. FERRIS AND HENRY L. FERRIS, OF HARVARD, ILLINOIS, ASSIGNEES TO
HUNT-HELM-FERRIS & COMPANY, OF HARVARD, ILLINOIS, A CORPORATION OF
ILLINOIS.

HAY-CARRIER.

1,291,457.

Specification of Letters Patent. Patented Jan. 14, 1919.

Application filed May 8, 1917. Serial No. 167,175.

To all whom it may concern:

Be it known that we, HOWARD J. FERRIS and HENRY L. FERRIS, citizens of the United States, residing at Harvard, in the county of 5 McHenry and State of Illinois, have invented a new and useful Improvement in Hay-Carriers, of which the following is a specification.

Our invention relates to certain new and 10 useful improvements in hay-carriers, and is fully described and explained in the specification and shown in the accompanying drawings, in which:

Figure 1 is a side elevation of my hay- 15 carrier; Fig. 2 is an end view; Fig. 3 is a section on the line 3 of Fig. 2, and Fig. 4 is a section on the line 4 of Fig. 3.

The present invention is particularly applicable to sling carriers of that type in 20 which the rope is gripped as distinguished from carriers of the fork type in which the fork pulley is directly gripped by holding means on the carrier frame. We have shown our present invention as embodied in a sling 25 carrier of the general type shown in Letters Patent No. 1,207,285, issued December 5, 1916, to Hunt, Helm, Ferris & Company as the assignee of Henry L. Ferris. The invention, however, is applicable to other 30 forms of sling carriers, that is to say, those provided with sling pulleys running in a bight and where the load is held in elevated position by clamping mechanism engaging the rope. Since the present structure is very 35 similar in its general features to the structure of said patent, we have neither illustrated all the details of its construction nor shall we describe the same with unnecessary particularity.

Referring to the drawings, 5 is the carriage running upon a track 6 and having swiveled to it a frame-work 7 carrying the operative parts of the mechanism. 8 is a hook movable with the trip member and to 40 it is attached one end of a chain 9 in the bight of which are hung the sling pulleys 10, the chain running up and over the pulley 11 carried in a housing 12 pivoted at its upper end to the swiveled frame and thereby capable of being swung out laterally 45 as the bight broadens when picking up a load. 13 is a locking member, it being of bifurcated form straddling the pulley 12 and one of its furcations is provided with 50 a segmental gear 14 meshing with a segmen-

tal gear 15 connected by a link 16 to the trip member 17 which is of ordinary form and operates in the usual manner in coöperation with a trip block 18. 19 is the releasing member which, when raised, operates the usual dog so as to free the trip member and let it fall.

The operation of the present device will be readily understood by those skilled in the art, particularly with reference to the 65 patent above identified, it being understood that when the carrier is in position where the trip member engages the trip block, the locking mechanism is released and the sling pulleys can be drawn down to receive their 70 load in the usual manner, the carrier being held against longitudinal movement on the track by the trip block. When the load is elevated the releasing member 19 is raised by engagement with the sling pulleys and 75 the trip member falls, not only by its own weight but with the added power given by reason of the fact that half of the load is hung upon it. As it descends it rocks the 80 segmental gears 14 and 15 and throws the locking mechanism into operation. The rise of the load thus frees the carrier from the trip block and at the same time locks the load so that the power upon the rope will draw the carrier along the track to its des- 85 tination.

The important point about the present arrangement is that we have provided means whereby abrasion of the cable and very annoying incidents thereof are entirely eliminated. The structure of the patent referred to was designed to reduce abrasion to the greatest possible extent, yet in practice it was found not to be wholly eliminated. It is necessary in hay-carriers to use a large 90 and expensive rope, or else a steel cable of relatively expensive character, and the constant renewal of rope or cable is both inconvenient and expensive.

In accordance with our invention we have 100 employed, as illustrated, a short length of chain at that end of the rope or cable adjacent to the carrier. It would be impossible to employ chain as a substitute for the entire length of rope or cable, on account of the 105 weight and expense, but we have discovered that it is entirely possible to use a short length of chain at that point where the clamping mechanism most frequently works. To this end we attach to the end of the rope 110

proper, indicated at 20, a hollow tubular fitting 21 terminating in an eye 22, the fitting 21 being firmly attached to the end of the rope and being of such size that it will run over the pulley and through the clamping mechanism when the same is released. The pulley is also centrally grooved so that the chain will fit nicely therein without twisting. This arrangement, of course, is equally applicable to a steel cable of smaller diameter, and such cable will run conveniently over the same pulley, it being nicely guided by the central groove in which the chain links fit.

We thus provide, at but slightly added expense, a carrier of the sling type which is wholly free from the greatest objection heretofore associated with such carriers. The upkeep cost of this carrier is no greater than that of a fork carrier, the chain being practically indestructible. The lock mechanism is entirely satisfactory and takes a firm and instant grip upon the chain without the possibility of damaging the same.

What we claim as new and desire to secure by Letters Patent is:—

1. In combination, a track, a carriage movable thereon, a trip block on the track, a trip member coöperating with the block, a pair of sling pulleys, clamping mechanism and a composite flexible member composed partly of rope and partly of chain, the chain portion only of said composite member passing through the clamping means, and such chain portion being so positioned as to be gripped thereby by frictional contact with the links when the sling pulleys are elevated.

2. In combination a track, a trip block thereon, a traveling carriage, a trip member coöperating with the trip block, clamping mechanism operated by the trip member, trip-releasing means, a pair of sling pulleys adapted to operate the same when raised, a

composite flexible member partly formed of rope and partly of chain, the chain portion only of which passes through the clamping mechanism and formed into a bight including the sling pulleys, such chain portion being so positioned to lie within the clamping mechanism when the sling pulleys are elevated to release the trip member.

3. In combination a track, a trip block thereon, a traveling carriage, a trip member coöperating with the trip block, clamping mechanism operated by the trip member, trip-releasing means, a pair of sling pulleys adapted to operate the same when raised, a composite flexible member partly formed of rope and partly of chain, the chain portion only of which passes through the clamping mechanism and formed into a bight including the sling pulleys, such chain portion being so positioned to lie within the clamping mechanism when the sling pulleys are elevated to release the trip member, and the flexible member receiving partial support from parts connected with the clamping mechanism, whereby the weight of the load carried by the sling pulleys is operated to grip the chain.

4. In combination, a track, a carriage movable thereon, a sheave carried by the carriage, clamping mechanism and means for releasing the same, sling pulleys, a composite member formed into a bight supporting the sling pulleys and passing over the sheave and through the clamping mechanism, said member being formed partly of rope and partly of chain, the chain portion being so positioned as to lie within the clamping member when the bight is shortened to elevate the sling pulleys.

In testimony whereof, we have hereunto set our hands this 18th day of April, 1917.

HOWARD J. FERRIS.
HENRY L. FERRIS.
